UNITED STATES PATENT OFFICE

2,683,618

AUTOMATIC PICKUP DEVICE

Joel B. Long, Fort Lauderdale, Fla., assignor of
one-half to Louis Slovis, Knoxville, Tenn.

Application December 11, 1950, Serial No. 200,169

2 Claims. (Cl. 294—65.5)

1

This invention relates to new and useful improvements in hand tools and the primary object of the present invention is to provide a device for retrieving or picking up small objects of magnetic material such as steel screws, nuts, cotter keys, springs, washers or the like.

Another very important object of the present invention is to provide a magnet pick up device including a flexible support to which is secured a permanent magnet whereby the device may be readily bent to reach around obstructions, curves or recesses during the retrieving or picking up of small metal objects.

A further object of the present invention is to provide a magnet pick up device including a flexible shank that slidably supports a flexible rod together with novel and improved means for sliding the rod in the shank to selectively move a magnet mounted on the rod into and out of a guide tube secured to the shank.

A still further aim of the present invention is to provide a device of the aforementioned character that is simple and practical in construction, strong and reliable in use, small and compact in structure, neat and attractive in appearance, inexpensive to manufacture, assemble and service, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of the present invention and with parts broken away for the convenience of explanation;

Figure 2 is a transverse vertical sectional view taken substantially on the plane of section line 2—2 of Figure 1;

Figure 3 is a detail view partly in section and partly in elevation showing the manner in which the trigger is operatively connected to the magnet holding rod;

Figure 4 is a perspective view of the trigger used in the present invention;

Figure 5 is an enlarged fragmentary view of the flexible tubular shank used in the present invention;

Figure 6 is a fragmentary view showing the device in slightly modified form including a sliding button for retaining the magnet exposed from its guide; and,

Figure 7 is a vertical sectional view taken substantially on the plane of section line 7—7 of Figure 6.

Referring now to the drawings in detail, wherein for the purpose of illustration, there is disclosed a preferred embodiment of the present invention, the numeral 10 represents a hand grip

2

whose upper portion 12 is formed with a bore 14 having a threaded entrance opening 16 and a reduced rear portion 18.

A flexible tubular shank 20 of woven or braided metal includes a rear end that is fixed by welding or the like to a tubular bolt or plug 22. The bolt 22 is threaded in the entrance opening 16 and its head abuts the forward face of the portion 12. The forward externally threaded end 24 of the shank 20 receivably engages a nut 26 that is suitably fixed to the rear end of a guide tube 28 in which there is slidably received a permanent magnet 30.

A relatively thin flexible wire cable or shaft 32 is slidably received within the shank 20 and its forward end is suitably fixed to the rear end of the magnet 30. The rear, enlarged, cylindrical end 34 of the shaft or rod 32 is slidably received in the rear end portion 18 of the bore 14 and supports a pair of abutments or rings 36 and 38 that are slidably received in the forward portion of the bore 14.

The hand grip 10 is formed with a slot 40 that intersects the bore 14. A pivot 42 extends transversely through the upper walls of the slot 40 and through a transverse opening 44 provided in the upper portion of a trigger or actuator 46 that is adapted to move into and out of the slot 40. A pair of rounded ears 48 extend upwardly from the trigger 46, enter the bore 14 and straddle the portion 34 between the abutments 36 and 38.

The rear face of the trigger, adjacent its lower end, is formed with a transverse recess 50 that receives one end of a coil spring 52. The other end of the spring 52 enters the slot 40 and yieldingly embraces a lug 54 on the rear wall of the slot 40. The spring 52 yieldingly urges the trigger from the slot 40 and the shaft 32 rearwardly to confine the magnet 30 in the guide tube 28.

The rear portion 18 of the bore 14 is closed by a plug 56 that is threaded therein and the hand grip 10 is integrally formed with a hook 58 that rises from the portion 12 whereby the device may be hung from a supporting structure when not in use.

In practical use of the present invention, the trigger 46 is manually urged into the slot 40 whereupon the ears 48 ride against the abutment 36 to force the magnet from the guide tube 30. As the trigger is released by the user, the spring 52 returns the trigger to its normal position with the ears 48 riding against the abutment 38 to return the magnet into the guide tube.

The flexibility of the shank 20 and rod 32 will permit the device to be employed for its intended use regardless of obstructions, curves, recesses or the like.

Means is provided for retaining the magnet 30 exposed from the guide tube 28 and this means consists of an extension 55 on the plug 56 that

will engage the end portion 34. A manual adjustment of the plug 56 in the rear end portion 18 will cause the rod 32 and magnet 30 to be locked or retained in their forward position with the magnet exposed for use.

Figures 6 and 7 show the means for retaining the magnet exposed from the guide 30 in slightly modified form. In this embodiment, the end portion 34a of the flexible shaft is formed with a peripheral groove 34b that will receive a lug 35 on a slide button or retainer 37 when the shaft 32 is disposed in its forward position with the magnet 30 exposed from the guide 28. The wall of the handle 10 is provided with a slot 39, disposed transversely of the shaft 32 and which slot slidably receives the shank of the button 37.

The flexible tube may be bent to any desired angle and will remain as bent until manually changed. It is preferred that a magnet presently being manufactured under the name Alnico, be used in the device since such a magnet is more practical and durable than other types.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A magnetic pick up device comprising a pistol grip handle, a flexible tubular shank attached at one end to the handle, a flexible shaft slidably received in the shank and including a forward end projecting outwardly from the shank, a mag-

net secured to the forward end of said shaft, a guide tube secured to said shank and slidably receiving said magnet, a trigger pivoted to the handle and engaging the shaft to slide the shaft within the shank and selectively move the magnet into and out of the guide tube, and spring means acting on said trigger to urge the shaft toward the handle and the magnet within the guide tube.

2. A magnetic pick up device comprising a pistol grip handle, a flexible tubular shank attached at one end to the handle, a flexible shaft slidably received in the shank and including a forward end projecting outwardly from the shank, a magnet secured to the forward end of said shaft, a guide tube secured to said shank and slidably receiving said magnet, said handle having a bore slidably receiving the rear end of said shaft, said handle also having a slot intersecting said bore, a trigger pivoted to said handle for movement into and out of said slot, spring means engaging the trigger and yieldingly urging the trigger from the slot, a pair of abutments on the rear end of said shaft, and a pair of ears on said trigger extending into the bore and straddling said shaft between said abutments, said trigger being manually urged into said slot for sliding the shaft forwardly to expose the magnet from the guide tube.
